AMPLIFYING SYSTEM

Charles S. Root, Bridgeport, Conn., assignor to
General Electric Company, a corporation of
New York

Application November 19, 1940, Serial No. 366,250

6 Claims. (Cl. 179—171)

My invention relates to amplifying systems and more particularly to amplifiers of high frequency potentials. In greater particularity, my invention relates to an improved and simplified arrangement for compensating, in an amplifier of this type, the effect of the retroactive currents which flow through the inherent anode-grid interelectrode capacity of an electron discharge device employed in high frequency signal amplifiers.

This application is a continuation-in-part of my application, Serial No. 223,179, filed August 5, 1938, now Patent 2,226,074, granted December 24, 1940, and assigned to the same assignee as the present invention.

One of the factors which limits the maximum amplification obtainable in a single stage of amplification is the regenerative action inherently present in the amplifier as a result of the interelectrode capacity, particularly the anode-grid capacity, of an electron discharge device employed in the amplifier. This interelectrode capacity serves to couple the output circuit of the discharge device to the input circuit of the device and eventually leads to uncontrollable free oscillation of the amplifier stage when an attempt is made to realize greater amplification beyond a certain point. Where two or more stages of high frequency amplification are used, sufficient amplification can usually be realized without extending the amplification of any one stage into the regenerative region when a state of free oscillation is likely to occur. Where, however, it is possible to employ only a single stage of amplification, it has been common practice to allow a certain amount of regeneration to exist in order that the amplifier stage may produce a greater output since it has been found exceedingly difficult to reduce the regeneration sufficiently to avoid its undesirable effects without greatly reducing the amplification in so doing. The reduction of regeneration, where accomplished, has been effected in the past by the use of interstage coupling transformers having a lower voltage step-up ratio or having lower impedance windings for the purpose of providing a poorer impedance matching of the transformer to the amplifier tube, or by biasing the tube to a point on its operating characteristic where the voltage amplification of the tube is greatly reduced. These methods of reducing the regeneration accomplish their desired end only by effecting such a large reduction in the voltage gain between the input and output circuits of the electron discharge device that the feed-back of

energy through the electron discharge device of the amplifier stage becomes negligible. Such methods, however, result in a very inefficient arrangement and a considerable loss of amplification.

The detrimental effects of regeneration in an amplifier stage are at once evident when it is considered that the presence of regeneration causes first, a pronounced sharpening of the resonance curve of the amplifier, thereby to restrict the range of frequencies which may pass through the amplifier for a given selectivity; secondly, by greatly increasing the difficulty of alignment of intermediate frequency stages of amplification due to a certain amount of interaction between the several electron discharge devices with their interconnecting circuits, a condition which necessitates that all of the intermediate frequency transformer trimmer condensers must be carefully adjusted and readjusted before a final balance of the amplifier stage may be accomplished; and thirdly, by greatly increasing the difficulty of properly aligning an intermediate frequency amplifier for both narrow and broad frequency band-pass operation where the amplifier stage has its frequency response expanded as by any of the several types of expanding systems now in common use.

Furthermore, it is well-known that tuning of a receiver in which regeneration exists is always accompanied by a characteristic "swish" noise and a high level of "hiss" background when listening to weak signals. There is also great danger of uncontrollable free oscillation of the amplifier when the amplifier tube (or an associated component) happens to be at or near the maximum limit of the tolerance range of amplification that is necessary to allow the manufacture of radio tubes and components. Additional trouble occurs in large quantity production of radio receivers due to abnormal differences in gain and selectivity resulting from the large variations in regeneration caused by variations in manufactured parts, as mentioned above.

It is an object of my invention to provide an improved amplifier arrangement in which the regenerative action caused by the grid-anode interelectrode capacity of the amplifying electron discharge device may be completely compensated, even though the effect of such capacity may be small and therefore relatively difficult to compensate exactly, as where a screen grid type of electron discharge device is employed.

A further object of my invention is to neutralize or compensate in a high frequency amplifier

the regenerative effect of the grid-anode inter-electrode capacity by an improved arrangement which maintains the cathode of the discharge device at a slight radio frequency potential above ground by action of the output circuit radio frequency currents thereby to provide a potential in the cathode circuit which may be returned to the input circuit as a degenerative potential.

Another object of my invention is to provide an improved intermediate frequency amplifier whose frequency band characteristic may be expanded over a wide range of expansion values without destroying the symmetry of the response curve of the amplifier about the intermediate frequency.

A further object of my invention is to provide an amplifier, particularly of the intermediate frequency type, having greatly improved selectivity and stability characteristics and one whose degree of amplification, or gain, is very materially increased over that obtainable by the prior art amplifier arrangements.

Still another and more specific object of my invention is to provide substantially exact neutralization of undesired regenerative voltages fed back upon the grid of a high frequency amplifier through the grid-anode interelectrode capacity by feeding back voltages, developed across a common cathode impedance, which are of equal magnitude and opposite phase with respect to the undesired voltages.

It is also specifically an object of my invention to provide an improved practical amplifier construction of this type wherein substantially exact neutralization may be obtained with inexpensive circuit elements of commercial quality and without recourse to expensive construction, careful shielding or critical adjustments.

The features of my invention which I believe to be novel are set forth with particularity in the appended claims. My invention itself, however, together with further objects and advantages thereof, may best be understood by reference to the following description taken in connection with the accompanying drawings, in which Fig. 1 diagrammatically illustrates an embodiment of my invention; Figs. 2 and 3 are equivalent circuit diagrams, Fig. 4 is a group of vector diagrams and Fig. 5 is a graph pertaining to the operation of my invention; Figs. 6 and 7 diagrammatically illustrate modified forms of my invention; Figs. 8 and 9 are further diagrams and Fig. 10 is another graph pertaining to the operation of my invention.

Referring now to Fig. 1 of the drawings, my invention is illustrated as embodied in an intermediate frequency amplifier stage of superheterodyne radio receiver. An electron discharge device 10 of the pentode type is illustrated, having electrodes including a control grid 11, a screen grid 12, a suppressor grid 13, an anode 14, and a cathode 15. Signal-modulated intermediate frequency oscillations are supplied through an input transformer 16 to the grid 11 and the cathode 15 of the device 10. The transformer 16 has a primary winding 17 coupled to a source of intermediate frequency oscillations, not shown, which may for example be a converter stage or a prior intermediate frequency amplifier stage in the usual superheterodyne receiver.

The secondary winding 18 of the input transformer 16 has one end connected to the grid 11 and the other end connected to the cathode 15 through a blocking capacitor 19 and an inductive impedance element 20. The lower end of the impedance element 20 is preferably maintained

at a relatively fixed reference potential by a connection to ground, as shown. The primary and secondary windings 17 and 18 are respectively tuned to the frequency of the intermediate frequency oscillations by the small trimmer capacitors 21 and 22. The capacitor 22 is connected directly between the grid 11 and the cathode 15.

A tertiary winding 23 is provided on the input transformer 16 for the purpose of varying the frequency band response of the amplifier. When the switch 24 is in the upper position as shown, the winding 23 is excluded from the grid circuit. Under these conditions the windings 17 and 18 are so coupled that the amplifier is highly selective. The winding 23 is arranged to overcouple the secondary circuit with the primary circuit of the transformer 16 when the switch 24 is manually moved from the upper switch contact 25 to the lower switch contact 26. Overcoupling the windings in this manner provides a broad frequency band response with resulting high fidelity operation of the amplifier and minimizes distortion associated with inaccuracies of present-day mechanical tuning of the receiver input circuit, as will readily be understood by those skilled in the art. The introduction of the winding 23 into the tuned secondary circuit in this manner does not appreciably detune this circuit since the inductance of the winding 23 is relatively insignificant in comparison to the much larger inductance of the transformer secondary winding 18.

The output circuit of the electron discharge device 10 is connected between the anode 14 and the cathode 15. This includes the primary winding 28 of an output intermediate frequency transformer 27 and a source of anode potential, not shown, whose positive terminal is connected to the conductor 30 and whose negative terminal is connected to ground. The transformer 27 has a secondary winding 29 connected to supply the amplified intermediate frequency oscillations to a utilization circuit, not shown, which may serially include further stages of amplification, a demodulating device, an amplifier of the modulation components of the intermediate frequency oscillations and a translating device.

The primary winding 28 and the secondary winding 29 of the output transformer 27 are tuned to the frequency of the intermediate frequency oscillations by the trimmer capacitors 31 and 32 respectively. The lower end of the output transformer winding 28 is maintained at ground potential for currents of intermediate frequency by means of a bypass capacitor 33.

A positive potential is applied to the screen grid 12 through a resistor 34 connected to the positive terminal of the source of anode potential. A bypass capacitor 35 maintains the screen grid at ground potential for currents of intermediate frequency.

The control grid 11 of the device 10 has a normal operating bias applied thereto from any suitable unidirectional potential source, not shown, having one terminal connected to the conductor 36 and the other terminal to ground. The control grid 11 may additionally have impressed thereon an automatic volume control bias supplied from a demodulator device, not shown, which demodulates the output of the intermediate frequency stage of amplification and supplies a potential to the conductor 36 whose magnitude varies with the average amplitude of the intermediate frequency oscillations. The purpose is to maintain the output of the ampli-

fier substantially constant notwithstanding the fact that the input signals may vary over a wide range of signal strength as is well understood in the art. The several interelectrode capacities of the electron discharge device are represented in Fig. 1 by the broken lines. The grid to cathode capacity is represented by the capacity C_{gc} , the anode to grid capacity by the capacity C_{pg} and the anode to cathode capacity by the capacity C_{pc} . If the capacity C_{pg} could be made zero, the output circuit of the discharge device 10 could be completely isolated from the input circuit of the device and the amplifier stage could be operated at its maximum possible amplification without experiencing the detrimental effects of regenerative feedback. However, much the capacity C_{pg} may be reduced by the use of the screen grid 12, there nevertheless exists a small capacity between the anode and grid elements of electron discharge devices customarily used at the present time. The regenerative feed-back of energy through the capacitor C_{pg} , unless compensated by a corresponding degenerative feed-back of energy in the manner of my invention, not only prohibits the attainment of the maximum amplification which is otherwise possible in the amplifier arrangement, but additionally introduces into the operation of the amplifier the detrimental effects of regeneration considered heretofore.

It will be observed that the anode circuit for the device 10 includes the output tank circuit 28, 31, and the inductive element 20 in series. It is important to note that the anode circuit has in shunt thereto the anode to cathode capacity C_{pc} of the device 10. Therefore, when the primary circuit of the transformer 27 is tuned to resonance at the operating frequency of the amplifier, the net reactance of the tank circuit 28, 31, alone is inductive since it is deficient in capacity by the small capacity C_{pc} . The anode circuit may therefore be considered as a voltage divider for the intermediate frequency potentials developed in the anode circuit, having two inductive elements in series.

The inductive impedance 20 is also connected in series with the winding 18 and the capacitor 22 in the grid tank circuit. The radio frequency potentials developed on impedance 20 by the flow of anode current therethrough are consequently impressed on the grid 11 through the winding 18, which is also highly inductive. As is fully explained in my aforesaid Patent No. 2,226,074, December 24, 1940, and as will be further developed herein, these circuit connections provide a degenerative feed-back to the grid 11. If the magnitude and phase of the potentials which are fed back to the grid 11 through the impedance 20 are properly adjusted with respect to the regenerative potentials fed back to the grid 11 from the anode 13 through the inherent capacity C_{pc} , the regenerative potentials are neutralized or compensated.

In the usual design of an amplifier of this type, the windings of the transformers 16 and 27 are constructed so as to have a relatively high ratio of reactance to resistance at the operating frequency. This ratio is generally designated by the symbol Q . Coils of high Q are desirable from the standpoint of improved selectivity and gain in the amplifier, as will be apparent to those skilled in the art without further explanation.

In the practical design of an amplifier built in accordance with the teachings of my Patent No. 2,226,074, December 24, 1940, the resistances

present in the circuits have heretofore been considered to be negligible, in comparison to the inductive and capacitive reactances at the intermediate frequency, for the ordinary case of an amplifier having tank circuits of reasonably high Q . By making this assumption the practical determination of the circuit constants is simplified considerably since only pure reactances need be considered. That this assumption is not unreasonable has been amply demonstrated by the fact that amplifiers built in accordance with these teachings have gone into extensive use with very satisfactory results. From this it might be concluded that the higher the Q of the circuit elements the more nearly theoretically perfect neutralization can be approached. Nevertheless, even with the use of relatively expensive coils of high Q for the inductive elements of the circuit branches, the actual results have been found to fall somewhat short of practical realization of the benefits which should be attainable. The reason for this is that even with high Q coils it has heretofore been found necessary to provide a greater degree of neutralization than is theoretically necessary to remove all the effects of regeneration. This over-neutralization, or degeneration, reduces the amplifier gain too much, so that lesser degeneration is necessary, which in turn increases the difficulty of aligning the tuned circuits and causes dissymmetry of the frequency response curve, especially when band expansion is employed. Thus, many of the deleterious effects of regeneration are not completely eliminated unless an excessive loss of gain is tolerated.

Further investigation has revealed that substantially exact neutralization, together with surprising improvements in amplifier operating characteristics, can be obtained in a practical amplifier construction, if the resistance of these circuits is taken into consideration. It has been discovered that the apparent resistance of the circuit branches is in fact not negligible even though the individual elements may have a reasonably high Q . Surprisingly enough, it has been found, if the resistance is considered, it is not necessary to employ expensive circuit elements of high Q . Rather, practical attainment of these materially improved results requires only that the input and output transformer windings be of commercial quality; and even more unexpected is the fact that certain of the other circuit elements must then necessarily be of inexpensive, low- Q construction. These facts will become apparent from a consideration of the circuit analysis now to be developed in detail.

The alternating current circuits of the amplifier of Fig. 1 are represented in simplified form by the equivalent circuit diagram of Fig. 2. The tank circuit impedance between anode 14 and ground is represented by the two circuit branches within the dashed rectangle Z_1 . The branch comprising the winding 28 has both inductive reactance and resistance at the operating frequency and is shunted by the branch comprising the capacitive reactance provided by the capacitor 31, the distributed coil capacity and various stray capacities of the elements and connecting leads with respect to ground. The elements within the rectangle Z_1 are thus to be taken to include all the electrical constants, lumped and distributed, which make up the terminal impedance seen looking into the output tank circuit. As previously mentioned, this cir-

cuit has a net inductive reactance at the operating frequency of the amplifier since it is tuned to resonance by the small anode to cathode capacity C_{PC} . As is well known, an LC circuit which is very near resonance becomes, in effect, a very large resistance in series with an approximately equal value of reactance, in this case an inductive reactance. Thus, Z_1 has a very large terminal resistance and also an approximately equal value of terminal inductive reactance. Consequently, even though the winding 28 alone may be of fairly high Q, the net impedance Z_1 is of relatively low Q because the reactance and resistance are approximately equal and the resistance component thus cannot be considered negligible.

The impedance between cathode 15 and ground is represented in Fig. 2 by the inductance and resistance within the rectangle Z_2 . The anode to grid capacity C_{PG} , which is practically pure

$$\dot{E}_F = \dot{E}_p \left[\frac{\dot{Z}_4 \dot{Z}_1 \dot{Z}_G + \dot{Z}_3 \dot{Z}_1 \dot{Z}_G + \dot{Z}_3 \dot{Z}_1 \dot{Z}_4 + \dot{Z}_2 \dot{Z}_3 (\dot{Z}_4 + \dot{Z}_1) + \dot{Z}_2 \dot{Z}_G (\dot{Z}_1 + \dot{Z}_3 + \dot{Z}_4)}{\dot{Z}_4 \dot{Z}_1 \dot{Z}_G + \dot{Z}_3 \dot{Z}_1 \dot{Z}_G + \dot{Z}_3 \dot{Z}_1 \dot{Z}_4 + \dot{Z}_2 \dot{Z}_3 (\dot{Z}_4 + \dot{Z}_1) + \dot{Z}_2 \dot{Z}_G (\dot{Z}_1 + \dot{Z}_3 + \dot{Z}_4)} \right] \quad (6)$$

capacitive reactance, is comprised by Z_3 . The net terminal impedance of the input winding 18 between grid 11 and ground, taking into account its inductance, resistance and distributed capacity, comprises inductive reactance and resistance, as indicated within the rectangle Z_4 . The grid to cathode impedance Z_G includes the trimmer capacitor 22 and the inherent grid to cathode capacity C_{GC} in parallel and is practically pure capacitive reactance. Thus, the inductive and capacitive branches of the input tank circuit are comprised by the impedance Z_4 and Z_G , respectively. The impedances of the capacitors 19 and 33 are so low at the operating frequency that they can be neglected.

For the purposes of mathematical analysis the equivalent circuit diagram of Fig. 2 can be redrawn in generalized schematic form as the four-terminal network of Fig. 3. This figure represents the impedance network looking from the output circuit of the amplifier to the input circuit. The voltage $\dot{E}_F$ appearing between the anode P and the cathode C is fed back through the impedance network comprised by Z_1 , Z_2 , Z_3

$$R^2 = - \frac{(R_1 + R_4)(R_4 R_1 - X_4 X_1) + (X_1 + X_4 - X_3)(R_4 X_1 + R_1 X_4)}{(R_1 + R_4)^2 + (X_1 + X_4 - X_3)^2} \quad (8)$$

$$X_2 = - \frac{[(R_4 X_1 + R_1 X_4)(R_1 + R_4) - [(R_4 R_1 - X_4 X_1)(X_1 + X_4 - X_3)]}{(R_1 + R_4)^2 + (X_1 + X_4 - X_3)^2} \quad (9)$$

and Z_4 to the grid G. The condition for neutralization is that $\dot{E}_F$, the net resultant feedback voltage developed across the impedance Z_G between the grid G and the cathode C, shall be equal to zero for any value of $\dot{E}_F$ at the operating frequency of the amplifier. In other words, for exact neutralization the network of Fig. 3 is an infinite attenuation network having infinite attenuation between input terminals P and C and the output terminals G and C at the frequency to be amplified.

The first step toward determining the constants of the network which will satisfy this condition is to obtain a solution for $\dot{E}_F$ in terms of $\dot{E}_F$. This solution may readily be obtained by application of Kirchhoff's laws to the network. For this purpose, assume the three clockwise circulating currents I_1 , I_2 and I_3 , as shown in Fig. 3. In the following three equations, which may be written immediately from an application of Kirchhoff's laws, and in the subsequent equations, it is to be understood that a dot placed over a symbol indicates that it is

vector quantity. Otherwise a symbol denotes a scalar quantity.

$$\dot{E}_p - I_2 \dot{Z}_3 - \dot{E}_F = 0, \text{ or } I_2 = \frac{\dot{E}_p - \dot{E}_F}{\dot{Z}_3} \quad (1)$$

$$\dot{E}_F - I_3 \dot{Z}_G = 0, \text{ or } I_3 = \frac{\dot{E}_F}{\dot{Z}_G} \quad (2)$$

$$(I_2 - I_1) \dot{Z}_1 + (I_2 - I_3) \dot{Z}_4 + I_2 \dot{Z}_2 = 0 \quad (3)$$

Expanding Equation 3 and substituting values from Equations 1 and 2:

$$I_1 = \frac{(\dot{E}_p - \dot{E}_F)(\dot{Z}_1 + \dot{Z}_3 + \dot{Z}_4) - \dot{E}_F \dot{Z}_4}{\dot{Z}_1 \dot{Z}_2} \quad (4)$$

Also:

$$(I_3 - I_1) \dot{Z}_2 + (I_3 - I_2) \dot{Z}_4 + \dot{E}_F = 0 \quad (5)$$

Substituting values in Equation 5 from Equations 1, 2 and 4 and simplifying, the general equation for feedback voltage $\dot{E}_F$ is:

$$\dot{Z}_1 \dot{Z}_2 \dot{Z}_G + \dot{Z}_2 \dot{Z}_G (\dot{Z}_1 + \dot{Z}_3 + \dot{Z}_4) + \dot{Z}_3 \dot{Z}_1 \dot{Z}_4 + \dot{Z}_2 \dot{Z}_3 (\dot{Z}_4 + \dot{Z}_1) + \dot{Z}_2 \dot{Z}_G (\dot{Z}_1 + \dot{Z}_3 + \dot{Z}_4) = 0 \quad (6)$$

In order to satisfy the requirement that $\dot{E}_F$ be equal to zero, set the numerator of Equation 6 equal to zero, from which

$$\dot{Z}_2 = - \frac{\dot{Z}_4 \dot{Z}_1}{\dot{Z}_1 + \dot{Z}_3 + \dot{Z}_4} \quad (7)$$

Equation 7 expresses, in general terms, the relationship between $\dot{Z}_2$ and the other network constants which will provide exact neutralization in accordance with my invention. In order to obtain a solution for the particular circuit of Figs. 1 and 2, the next step is to substitute the vector quantities for the various impedances. In this particular case, these quantities are:

$$\dot{Z}_1 = R_1 + jX_1 \text{ (resistive and inductive)}$$

$$\dot{Z}_2 = R_2 + jX_2 \text{ (resistive and inductive)}$$

$$\dot{Z}_3 = -jX_3 \text{ (capacitive only)}$$

$$\dot{Z}_4 = R_4 + jX_4 \text{ (resistive and inductive)}$$

Upon substitution of these quantities in Equation 7, it is found that the general expressions for R_2 and X_2 are:

$$R^2 = - \frac{(R_1 + R_4)(R_4 R_1 - X_4 X_1) + (X_1 + X_4 - X_3)(R_4 X_1 + R_1 X_4)}{(R_1 + R_4)^2 + (X_1 + X_4 - X_3)^2} \quad (8)$$

$$X_2 = - \frac{[(R_4 X_1 + R_1 X_4)(R_1 + R_4) - [(R_4 R_1 - X_4 X_1)(X_1 + X_4 - X_3)]}{(R_1 + R_4)^2 + (X_1 + X_4 - X_3)^2} \quad (9)$$

Equations 8 and 9 are cumbersome. However, by making certain assumptions, which are those generally true in an amplifier of this type, they can be much simplified. The first of these assumptions is that the Q of the windings 18 and 28 is reasonably high. Most coils used in amplifiers of this type have a Q of at least 50, and usually higher, which is sufficient to meet this requirement. The second assumption is that the reactance X_3 of the anode to grid capacity C_{PG} is very large at the operating frequency as compared to the reactances of the windings 18 and 28. This is always true, and X_3 is especially large when the device 10 is provided with a screen grid. If these assumptions are made, then the following expressions hold good, with negligible error, in a practical embodiment of the amplifier of Fig. 1:

$$R_2 = \frac{R_4 X_1 + R_1 X_4}{X_3} \quad (10)$$

$$X_2 = \frac{X_4 X_1 - R_1 R_4}{X_3} \quad (11)$$

where

R_1 and X_1 =the resistance and reactance between anode and ground,
 R_2 and X_2 =the resistance and reactance between cathode and ground,
 X_3 =the reactance of the anode to grid capacity C_{PG} , and
 R_4 and X_4 =the resistance and reactance between grid and ground.

By dividing Equation 11 by Equation 10, the following single expression may also be obtained for the practical amplifier of Fig. 1:

$$Q_2 = \frac{Q_1 Q_4 - 1}{Q_1 + Q_4} \quad (12)$$

where Q_1 , Q_2 and Q_4 =the ratios of reactance to resistance of Z_1 , Z_2 and Z_4 at the operating frequency.

The vector diagram of Fig. 4 further illustrates graphically the relationship between the voltages in the several amplifier branches for the condition of exact neutralization. Fig. 4a is a vector diagram of the voltages between the anode P and cathode C. It will be seen that the voltage $\dot{E}_P$ is equal to the vector sum of the voltage drops $\dot{I}Z_1$ and $\dot{I}Z_2$, from anode to ground and from ground to cathode, respectively. Each of these vectors may further be resolved into the resistance and reactance drops through impedances Z_1 and Z_2 . These vectors also show qualitatively that the Q of Z_2 is somewhat less than the Q of Z_1 . As previously mentioned, the Q of the latter impedance will be quite low since the output tank circuit is very near resonance. Therefore, the Q of the cathode impedance Z_2 will also be low.

The vector diagram of Fig. 4b represents the voltages fed back from the cathode to the grid from the cathode impedance Z_2 . The voltage drop $\dot{I}Z_2$ produces the drops $\dot{I}R_4$ and $\dot{I}X_4$ through the impedance Z_4 . Since the grid to cathode impedance C_{GC} is almost purely capacitive, the drop $\dot{I}Z_4$ is in phase opposition to the $\dot{I}X_4$ drop.

The vector diagram of Fig. 4c represents the voltages fed back from the anode to the grid through the anode to grid impedance Z_3 . Since the impedances Z_3 and Z_G are both almost purely capacitive, the voltages $\dot{E}_{Z_3}$ and $\dot{E}_{Z_G}$ across them will be in phase, as shown.

If the circuit constants are selected in accordance with the equations previously developed, then the voltages $\dot{I}Z_G$ and $\dot{E}_{Z_G}$ are exactly equal and in phase opposition. Figs. 4b and 4c illustrate this condition. The net voltage between the grid and cathode due to $\dot{E}_P$ will therefore be zero.

In a typical amplifier of the type shown in Fig. 1 the intermediate frequency might be equal to 455 kc., the capacity C_{PG} equal to .005 mmf., the anode to cathode capacity to C_{GC} equal to 5 mmf., the inductance of the windings 18 and 28 each equal to 2.45 mh., and the Q of each winding equal to 100. Using these values merely for illustration, calculations will readily show that

R_1 =about 8,400 ohms
 X_1 =about 76,000 ohms
 R_4 =about 70 ohms
 X_4 =about 7,000 ohms
 X_3 =about 70 megohms.

If these values are substituted in the simplified practical Equations 10, 11 and 12, it will be

found that substantially exact neutralization is achieved when R_2 equals 0.9 ohm and X_2 equals 7.6 ohms, approximately. Thus, the Q of the impedance 20 will be equal to about 8.4 which is quite low. This is entirely consistent with the preceding analysis since the Q of Z_1 is also low, being equal to about 9.0 in this case.

The graph of Fig. 5 shows selectivity curves for a typical superheterodyne receiver whose intermediate frequency amplifier circuits were provided with the neutralizing connections of Fig. 1. When windings 18, 20 and 28 were all designed to have high Q values, the curve A was secured. When the resistance of winding 20 was increased, in accordance with the present invention, so as to secure the proper phase relations between the feedback voltages, curve B resulted. It will be observed that the curve B provides a wider band pass for the same selectivity at 10 kc. from the center frequency, increasing the fidelity of audio reproduction. Stated in the converse, my invention therefore permits the receiver to be designed for greater selectivity with the same band pass characteristics. Furthermore, when the circuit constants were properly selected, it was no longer necessary to over-neutralize to remove all regenerative effects completely. Consequently, in this particular receiver a gain in sensitivity of about 1.5 times, or 50 per cent, was also achieved. The fact that the receiver fidelity and sensitivity were simultaneously improved to a marked extent for substantially the same selectivity demonstrates concretely the practical merit of my invention.

In my aforesaid Patent No. 2,226,074, December 24, 1940, a modified form of amplifier has been shown in which the common impedance between cathode and ground comprises a self bias resistor and a self bias capacitor in parallel. An amplifier of this form, which may be designed to give substantially exact neutralization in accordance with the principles of my present invention, is illustrated in Fig. 6. In many respects the circuit is similar to that of Fig. 1 and corresponding elements have been designated by corresponding reference numerals. The inductive impedance 20 is replaced by the resistor 37 and capacitor 38 in parallel. This necessitates certain changes in the manner of connecting the input circuit to the cathode 15 if the proper phase relationship between the regenerative and degenerative voltages is to be maintained. In this embodiment the trimmer capacitor 22 is connected between the grid 11 and ground, and the winding 18 is connected between the grid 11 and the cathode 15 through a blocking capacitor 40. For reasons that will shortly be apparent it is also generally necessary to include a resistor 39 in series with the capacitor 22, if exact neutralization is to be obtained in accordance with my invention.

The equivalent alternating current circuit diagram for Fig. 6 is illustrated in Fig. 8. This diagram is similar to that of Fig. 2 and corresponding symbols have been used. The cathode to ground impedance Z_2 now consists of equivalent series resistance and capacitive reactance. The grid to ground impedance Z_4 is also resistive and capacitive and the net grid to cathode impedance Z_G is resistive and inductive, since the inductance of the winding 18 predominates over the capacity in shunt thereto.

The analysis previously developed for the general network of Fig. 3 applies equally well to this amplifier circuit and Equation 7 expresses the

exact impedance relationships for neutralization. If the specific vector quantities for this embodiment are substituted for the impedances of Equation 7, and if the same simplifying assumptions are made as those which were made for the amplifier of Fig. 1, the resulting practical equations for the equivalent series resistance and capacitive reactance between cathode and ground are:

$$R_2 = \frac{R_4 X_1 - R_1 X_4}{X_3} \quad (13)$$

$$X_2 = \frac{X_4 X_1 + R_1 R_4}{X_3} \quad (14)$$

The Q of the cathode impedance Z_2 is expressed by

$$Q_2 = \frac{Q_1 Q_4 + 1}{Q_1 - Q_4} \quad (15)$$

It will be observed that Equations 13, 14 and 15 are in the same general form as Equations 10, 11 and 12 except for changes of sign. This makes one important practical difference. From Equation 13 it will be seen that $R_4 X_1$ must be at least equal to $R_1 X_4$. Otherwise R_2 will be a negative resistance, which is not physically realizable. Expressed another way, the ratio of X_1 to R_1 , or Q_1 , must be equal to or greater than the ratio of X_4 to R_4 , or Q_4 . This same fact is also apparent from inspection of the denominator of Equation 15. Q_1 is quite low, since the output circuit comprised by Z_1 is very near resonance, as previously explained. Since the trimmer capacity 22, which provides almost all of the reactive component of Z_4 , is of high Q , i. e., of very low resistance, the external resistance 39 must generally be inserted to make Q_4 at least as low as Q_1 .

Further analysis will show that the resistance of resistor 39 may necessarily be of considerable magnitude for exact neutralization in an amplifier having typical circuit constants. Since this resistance is included directly in the grid tank circuit, the grid circuit is damped and neutralization is secured only at the expense of loss of gain and selectivity in the ordinary case.

The circuit of Fig. 7 overcomes these disadvantages and still permits substantially exact neutralization with the resistor 37 and the capacitor 38 in the cathode circuit. The circuit of Fig. 7 differs from that of Fig. 6 in that the lower end of the winding 18 and the lower terminal of the trimmer capacitor 22 are both connected to ground through the blocking capacitor 19. A separate inductive impedance 41 completes the grid tank circuit from the grid 11 to the cathode 15 through the blocking capacitor 40.

The primary winding 17 may be coupled to the winding 18, as shown, or optionally coupled to the winding 41. Also, since the lower ends of both windings 18 and 41 are isolated from the cathode circuit for direct current by the blocking capacitors 19 and 40, A. V. C. potentials may be supplied to the grid 11 over the conductor 36, or optionally over the conductor 36', as shown in broken lines.

Fig. 9 represents the equivalent alternating current circuit for Fig. 7. It is electrically the substantial equivalent of Fig. 8. The closed tank circuit 18, 22 of Fig. 7 forms the capacitive branch Z_4 of the input network in this case. It is tuned to resonance at the operating frequency of the amplifier by the inductive reactance of the impedance 41 which forms the inductive branch Z_G . If the impedance 41 has large inductance, its reactance at the operating frequency will be large and the tank circuit 18, 22

will be very near to resonance. Therefore, the tank circuit 18, 22, will be capacitive, because it lacks the inductance 41, and highly resistive, because it is so near resonance. Thus, for the same reasons previously outlined for the case of Z_1 , the net terminal impedance Z_4 between grid and ground will have a relatively low Q , because the resistance is approximately equal to the reactance, which is capacitive in this case. Equation 7 and the simplified practical Equations 13, 14 and 15 can therefore be satisfied in this circuit so as to make R_2 positive without actually damping the grid tank circuit by the addition of external resistance. The proper phase shift through Z_4 for exact neutralization is thus secured without adverse effects upon the selectivity and gain of the amplifier.

It will be observed from an inspection of Figs. 2, 8 and 9, that Z_1 is always inductive since it is tuned to resonance at the operating frequency of the system by the anode to cathode capacity C_{PC} . The impedances Z_4 and Z_G are always of opposite sign, since Z_4 is included in one of the two parallel branches between the grid and cathode of the amplifier, and Z_G is included in the opposite branch, the two branches being tuned to resonance at the operating frequency. Finally, it will be noted that the common cathode impedance Z_2 must be of the same sign as Z_4 if the proper phase relations for neutralization are to be secured. If Z_2 and Z_4 are both inductive, Equations 10, 11, and 12 can be utilized for the practical case where the simplifying assumptions introduce negligible error. If these impedances are both capacitive, then Equations 13, 14, and 15 should be used for practical design calculations. In either case Equation 7 expresses, in general terms, the exact relationships of circuit constants in terms of the impedance vectors involved.

It will now be evident that I have accomplished by my invention the very complete and effective control of the magnitude of the regenerative action experienced in the prior art amplifier arrangements. The advantages which follow from the use of my invention are manifold. Fig. 10 is a graph illustrating, in a manner well known in the art, the frequency response of an intermediate frequency stage of amplification. The curve *a* represents the frequency response of a highly selective amplifier which, being selective, may completely fail to pass the higher audio frequencies. It has become customary to provide in high fidelity radio receivers or in mechanically tuned receivers some form of frequency response expanding arrangement whereby the frequency response of the amplifier may be expanded in a manner to allow the passage of the higher audio frequencies to obtain high fidelity reproduction of the modulated intermediate frequency oscillation whenever receiving conditions render the use of a highly selective arrangement unnecessary. One such arrangement, comprising the tertiary winding 23 and associated switching means, has been illustrated and described herein. These receivers are aligned in the narrow band-pass position to have the highly selective frequency response represented by the curve *a*. When, however, the frequency response is expanded in these receivers, the prior art amplifier arrangements no longer have a symmetrical response curve about the intermediate frequency (represented by the vertical line of Fig. 10) but have, by virtue of the regenerative action present in the prior art amplifiers, a distorted response curve with an abnormal double hump which may

be represented by the broken line *b* of Fig. 10. The peak at *c* is higher than at *d* because the grid to anode capacity (C_{PG} in Figs. 1, 6 and 7) produces greater regenerative feed-back at higher frequencies. This causes considerable distortion of the audio frequencies, thereby to produce a highly undesirable condition of operation. In addition, the operator is more apt to tune the receiver to the peak *c* than to the intermediate frequency, causing further distortion. My invention, by eliminating the effect of the regenerative action, not only renders the response curve of the amplifier symmetrical about the intermediate frequency throughout a large range of values of frequency expansion, but also flattens off the top of the response curve by reducing any double hump which would otherwise be present (according to the well-known tendency of degeneration to flatten off a frequency response characteristic of an amplifier), giving a frequency response curve as shown by the full line *e* in Fig. 10.

The neutralization of the regenerative currents in the amplifier allows the realization of the highest possible amplification or gain for each stage of amplification since the amplifier no longer has a tendency to break into free oscillation. The gain or amplification obtainable in an amplifier arrangement embodying my invention is limited only by the design of the amplifier input and output transformers and by the maximum amplification obtainable with the particular electron discharge device used.

My invention has the further advantage that the degenerative voltage not only originates in but is utilized in each individual amplifier stage and, therefore, the degenerative circuit does not include interstage coupling transformers whose value of magnetic coupling may be changed by expansion of the frequency band response. The neutralization of the regeneration effected within a single stage has an important advantage in that it is unnecessary to consider and to cope with phase shifts between the regenerative and degenerative currents where the degenerative voltage originates in an amplifier stage following or preceding the neutralized amplifier stage. A phase shift of this nature may perhaps be corrected for a given frequency band response of the amplifier at a given amplifier output, but the correction is improper for other values of frequency band response or for higher or lower amplification since changes in either the frequency response or the amplification results in corresponding changes in the phase and magnitude between regenerative and degenerative currents. For high fidelity reproduction, this requires that the intermediate frequency stages of amplification in the prior art arrangements be realigned for each and every value of frequency response expansion. The operating conditions of an amplifier embodying my invention do not affect the symmetry of the frequency band response about the intermediate frequency since the frequency response is unaffected throughout a large range of values of frequency expansion and is independent of the power output of the amplifier.

My amplifier arrangement has another important advantage. In the design of the prior art high gain single stage amplifiers which, at best, include as much regeneration due to grid to anode interelectrode capacity as can safely be tolerated, it becomes necessary to resort to great expense and trouble in reducing all other stray or circuit regeneration to an absolute minimum,

often at a sacrifice of flexibility of receiver layout and even of receiver performance. With my invention, such elaborate precautions are no longer necessary since slight amounts of stray regeneration can be tolerated, and my invention may be utilized to compensate both the additional regeneration and that introduced by the grid to plate capacity. This, of course, requires the furnishing of degenerative currents in excess of those which would normally be required.

Previous neutralizing circuits have involved the added cost and complexity of an additional neutralizing winding or critically positioned tap on the transformer and a small, critical neutralizing capacitor whose leads were at a high radio frequency potential above ground and therefore inherently non-stable. By contrast, my invention does not require any additional components over and above those required for prior art amplifiers but uses stable, low-potential cathode circuit components.

While I have shown particular embodiments of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. In combination, an amplifier having a cathode, a grid and an anode, an output circuit having one terminal connected to said anode and the other terminal connected to said cathode through an impedance element, said output circuit having a net terminal impedance $\dot{Z}_1$ and said element having an impedance $\dot{Z}_2$ at the operating frequency of said amplifier, each of said impedances having a relatively low ratio of reactance to resistance at said frequency, and an input circuit having a capacitive branch and an inductive branch, one of said branches being connected between said grid and said cathode, the other of said branches being connected between said grid and the point between said output circuit and said impedance element, said latter branch having a net terminal impedance $\dot{Z}_4$ at said operating frequency, the relationship between said impedances and the impedance $\dot{Z}_3$ due to the capacity between said anode and said grid being substantially expressed by the equation:

$$\dot{Z}_2 = - \frac{\dot{Z}_4 \dot{Z}_1}{\dot{Z}_1 + \dot{Z}_3 + \dot{Z}_4}$$

2. In a high frequency amplifying system, an electron discharge device having an anode, a cathode and a grid, an output circuit having a net terminal inductive reactance X_1 and a resistance R_1 at the operating frequency of said system, an impedance having a reactance X_2 of one sign and a resistance R_2 at said frequency, said output circuit having one terminal connected to said anode and the other terminal thereof connected to said cathode through said impedance, and an input circuit having an inductive branch and a capacitive branch, one of said branches having a terminal reactance X_4 of the same sign as said impedance and a resistance R_4 , said one branch being connected between said grid and the point between said output circuit and said impedance, the other of said branches being connected between said grid and said cathode, the relationship between said impedance, said circuits and the inherent anode

to grid capacitive reactance X_3 of said device being substantially expressed by the equations:

$$R_2 = \frac{R_4 X_1 \pm R_1 X_4}{X_3}$$

and

$$X_2 = \frac{X_4 X_1 \mp R_1 R_4}{X_3}$$

3. In combination, an amplifier having an anode, a cathode and a grid, an output circuit comprising an inductive branch and a capacitive branch and having a net terminal inductive reactance X_1 and a resistance R_1 at the operating frequency of said amplifier, an impedance having an inductive reactance X_2 and a resistance R_2 at said frequency, said output circuit and said impedance being serially connected between said anode and said cathode, and an input circuit comprising a second capacitive branch connected between said grid and cathode and a second inductive branch having reactance X_4 and resistance R_4 at said frequency connected between said grid and the point between said output circuit and said impedance, said impedance being between said point and said cathode, both of said inductive branches having a relatively high ratio of reactance to resistance at said frequency, the relationship between said impedance, said circuits and the inherent anode to grid capacitive reactance X_3 of said amplifier at said frequency being substantially expressed by the equations:

$$R_2 = \frac{R_4 X_1 + R_1 X_4}{X_3}$$

and

$$X_2 = \frac{X_4 X_1 - R_1 R_4}{X_3}$$

4. In combination, an amplifier having an anode, a cathode and a grid, an output circuit comprising an inductive branch and a capacitive branch and having a net terminal inductive reactance X_1 and a resistance R_1 at the operating frequency of said amplifier, an impedance having capacitive reactance X_2 and a resistance R_2 at said frequency, said output circuit and said impedance being serially connected between said anode and said cathode, and an input circuit comprising a second inductive branch connected between said grid and said cathode and a second capacitive branch having capacitive reactance X_4 and a resistance R_4 at said frequency connected between said grid and the point between said output circuit and said impedance, said impedance being between said point and said cathode, both of said inductive branches having a relatively high ratio of reactance to resistance at said frequency, the relationship between said impedance, said circuits and the inherent anode to grid capacitive reactance X_3 of said amplifier at said frequency being substantially expressed by the equations:

$$R_2 = \frac{R_4 X_1 - R_1 X_4}{X_3}$$

and

$$X_2 = \frac{X_4 X_1 + R_1 R_4}{X_3}$$

5. A tuned high frequency amplifying system comprising in combination, an electron discharge amplifier having electrodes including an anode, a cathode and a control grid, said electrodes having inherent capacity therebetween, a tunable output circuit comprising an inductance and

capacitance connected in parallel between said anode and ground, said circuit having a net terminal inductive reactance X_1 and a resistance R_1 when tuned to the operating frequency of said amplifier in conjunction with the inherent anode to cathode capacity, an inductive impedance having a reactance X_2 and a resistance R_2 connected between said cathode and ground, a tunable input circuit comprising a second inductance connected between said grid and ground and a second capacitance connected between said grid and cathode, said second inductance having a reactance X_4 and a resistance R_4 when said input circuit is tuned to said operating frequency, and means to impress potentials of said operating frequency upon said input circuit, said inductances individually having relatively high ratios of reactance to resistance at said operating frequency, the relationship between said reactances, resistances, and the reactance X_3 due to the inherent capacity between said anode and said grid being substantially expressed by the equations:

$$R_2 = \frac{R_4 X_1 + R_1 X_4}{X_3}$$

and

$$X_2 = \frac{X_4 X_1 - R_1 R_4}{X_3}$$

whereby potential variations at said frequency between said anode and cathode produce substantially no potential variations between said grid and cathode.

6. A tuned high frequency amplifying system comprising, in combination, an electron discharge amplifier having electrodes including an anode, a cathode and a control grid, said electrodes having inherent capacity therebetween, a tunable output circuit comprising an inductance and capacitance connected in parallel between said anode and ground, said circuit having a net terminal inductive reactance X_1 and a resistance R_1 when tuned to the operating frequency of said amplifier in conjunction with the inherent anode to cathode capacity, a capacitive impedance having a reactance X_2 and a resistance R_2 connected between said cathode and ground, a tunable input circuit comprising a second inductance and a second capacitance connected in parallel between said grid and ground and a third inductance connected between said grid and said cathode, said second inductance and second capacitance having a net terminal capacitive reactance X_4 and a resistance R_4 when tuned to the operating frequency of said amplifier together with said third inductance, and means to impress potentials of said operating frequency upon said input circuit, all said inductances individually having relatively high ratios of reactance to resistance at said operating frequency, the relationship between said reactances, resistances and the reactance X_3 due to the inherent capacity between said anode and grid being substantially expressed by the equations:

$$R_2 = \frac{R_4 X_1 - R_1 X_4}{X_3}$$

and

$$X_2 = \frac{X_4 X_1 + R_1 R_4}{X_3}$$

whereby potential variations at said frequency between said anode and cathode produce substantially no potential variations between said grid and cathode.

CHARLES S. ROOT.

CERTIFICATE OF CORRECTION.

Patent No. 2,250,206.

July 22, 1941.

CHARLES S. ROOT.

It is hereby certified that error appears in the printed specification of the above numbered patent requiring correction as follows: Page 1, second column, line 10, for "emplifier" read --amplifier--; page 2, second column, line 39, for "negtaive" read --negative--; page 4, first column, line 35, for the word "impedance" read --impedances--; and second column, line 13, Equation 4, for " $\dot{E}_p$ " read -- $\dot{E}_p$ --; line 38, for "particlar" read --particular--; page 5, first column, line 63, strike out "to" after "capacity"; page 6, second column, line 18, for "inspectiton" read --inspection--; page 7, second column, line 35, claim 1, for "impedance" read --impedance--; and that the said Letters Patent should be read with this correction therein that the same may conform to the record of the case in the Patent Office.

Signed and sealed this 16th day of September, A. D. 1941.

(Seal)

Henry Van Arsdale,
Acting Commissioner of Patents.
